UNITED STATES PATENT OFFICE.

GEORGE P. ALTENBERG, OF CINCINNATI, OHIO.

DESIGN FOR A BOTTLE-CASING.

No. 39,481.

Specification for Design.

Patented Sept. 1, 1908.

Application filed June 15, 1908. Serial No. 438,688. Term of patent 14 years.

To all whom it may concern:

Be it known that I, GEORGE P. ALTENBERG, a citizen of the United States, residing at Cincinnati, in the county of Hamilton and State of Ohio, have invented a new, original, and ornamental Design for a Bottle-Casing, of which the following is a specification, reference being had to the accompanying drawing, forming part thereof.

My new, original and ornamental design for a bottle casing is shown in the accompanying drawing, in which:

Figure 1 is a side elevation of the bottle casing; and, Fig. 2 is a top plan view of the same.

I claim:

The ornamental design for a bottle casing, as shown.

GEORGE P. ALTENBERG.
